UNITED STATES PATENT OFFICE

2,473,340

BOLSTER FOR FOUR-WHEEL COMMERCIAL
AND FARM TRAILERS

Otto A. Klockau, Rock Island, Ill.

Application January 24, 1947, Serial No. 724,183

3 Claims. (Cl. 280—143)

1

My invention has reference to a spring balanced bolster for four wheel commercial and farm trailers, and has for its purpose to equalize the shifting weight of the load, and absorb any shock producing movements so as to prevent the same from contacting the usual posts of the running gear, which might cause injury or breakage thereto.

One of the objects of the invention is to provide a unitary bolster support of a resilient character by means of which the load will be well balanced against lateral movement. This includes a double bolster formation, with a false or floating bolster, and springs interposed between the bolster plates of a character to help carry the load. Special features are made use of in carrying out this part of the invention.

Another purpose of the invention is to guard the trailer apparatus from lengthwise movement of the load, such as might result in breakage of the vehicle posts or other part of the equipment. When the trailer and its load come to a stop there is a tendency of the load to lunge forwardly, with a considerable strain on the posts, and when the vehicle is started there is a similar tendency, but in the opposite direction. A similar tendency is encountered when the vehicle is moving upwardly or downwardly on a grade. Means are provided in the present invention for compensating for this action, and preventing the same from being directed against the trailer posts or stakes.

The above named, and other features and advantages of the invention will more fully appear from the following specification, taken in connection with the accompanying drawing, in which,

Fig. 1 is a side view of a vehicle bed, with parts in section.

Fig. 2 shows one of the bolster units in side view.

Fig. 3 is a lower plan view of the upper bolster plate, detached.

Fig. 4 is a plan view of the lower bolster plate, detached.

Fig. 5 is an end view of the bolster unit.

Fig. 6 is a cross-section on the line 6—6 of Fig. 2 with parts broken away.

Referring first to Fig. 2, the number 8 indicates one of the axles of a four-wheel trailer, upon which is supported a bolster plate 9, with recesses 10 in its ends to accommodate a pair of posts 11 of usual construction, secured at the ends of the axle 8, as by bolts 12. Above the plate 8 is supported a false bolster plate 13, of inverted channel-plate formation, by means of heavy coiled springs 14, held in spaced relation with each other

2

near the ends of the bolster plates by means of circular detents 15, fitting into the lower coils of the springs. The lower face of the plate 13 is fitted with similar detents 16 and 17, in register with the detents 15, and engaged by the upper ends of the springs. The detents 17 are of greater length than the others, and are adapted for contact with the detents 15 just below them, to limit the closing action of the springs. The posts 11 are also preferably formed of channel-plate material, similarly to the plate 13.

The plate 13 is provided with recesses 20 in its ends, to accommodate movement of the plate vertically of the posts, with a little clearance between the posts and side edges of the recesses to permit independent movement of the plates. The posts are also fitted with lugs 19 midway their heights, which serve as stops and limit the upward movement of the plate 13, preventing any possible escape of the springs 14 from between the plates. Each of said posts has a base 21 which fits snugly into the opening in the plate 9, and keeps such posts from turning.

The operation of the device will be obvious. 25 The variation in the weight on the ends of the bolsters will be counterbalanced by the springs 14, and the load accommodated to changes in the surface of the road. It will have a floating movement with relation to the wagon gear parts of the trailer. It will be understood that the front end of the trailer is fitted with means for connection with a tractor or other traction vehicle, but not shown in the drawing.

In Fig. 1 is shown a pair of axles 8, united by 35 a reach 23, of tubular form, with a telescopic section 24, not new in the present device, and fixed to the reach 23 towards each end thereof are clamping collars 25, secured by ears 26 connected with a bolt 27, and similar ears 28 held together by pins 29, upon which the held the inner ends of chains 30, the other ends of which are fitted with threaded pins 31, inserted through openings 32 in the inner flanges 13a of the plates 13. The pins are provided with nuts on the inner and outer faces of the flanges 13a, as indicated at 33, and can be adjusted to increase or lessen the tension of the chains. Each of the chains is held reasonably taut, but has a limited amount of stretch, or "yield" to permit a rocking movement outwardly of the plate 13 to which it is attached. The strain which would otherwise be received by the post 11 is thereby applied to the chain, with the limited rocking movement of the upper bolster plate further controlled by the 45 springs 14 on which it rests. The chains are 50 55

oppositely disposed, so that one of them takes care of a lunging movement of the load toward the front, and the other one a similar movement to the rear.

The rocking movement of the springs 14, taken in connection with the yieldable restricting action of the chains 30 adds to the floating action already referred to, and makes the balancing support of the load complete.

Changes can be made in the manner of construction and operation of the invention without departing from the spirit of the invention, as set forth and claimed herein.

What I claim, and desire to secure, is—

1. In a device of the class described, the combination with a vehicle reach and axle attached thereto, and posts supported at the ends of said axle, of a two-part bolster mounted on said axle including a lower plate and upper plate having a vertically sliding connection with said posts, interposed springs, and a chain connection between said upper plate and said reach, permitting a limited rocking movement to said upper plate, independently of the posts.

2. In a device of the class described the combination with a vehicle frame, including a pair of axles and connecting parts, and posts supported from the ends of said axles, of a two-part bolster on each of said axles, including lower plates on said axles and upper plates spaced

5 above the same, having vertical play on said posts, and interposed springs, and chain connections between said upper plates and said frame parts, permitted limited rocking movements outwardly

of said upper plates.

3. In a device of the class described, the combination with a vehicle reach and axle attached thereto, and posts fixed on the ends of the axle and provided with stops midway their ends, a

10 two-part bolster mounted on said axle, including a removable lower plate, and an upper plate spaced therefrom having vertical play on said post, and limited in its upward movement by said stops, and a chain connection between said upper plate and said reach, provided at one of its ends with means for adjustment of the length thereof, and compression springs interposed between said plates.

20 OTTO A. KLOCKAU.
